UNITED STATES PATENT OFFICE.

ADOLPH STUETZEL AND HERMAN W. BOHN, OF BOSTON, MASSACHUSETTS; SAID STUETZEL ASSIGNOR TO SAID BOHN.

DESIGN FOR A TRINKET OR SIMILAR ARTICLE.

Application filed December 27, 1922. Serial No. 4,721. Term of patent 3½ years.

To all whom it may concern:

Be it known that we, ADOLPH STUETZEL and HERMAN W. BOHN, citizens of the United States of America, residing at Boston, in the county of Suffolk and Commonwealth of Massachusetts, have invented a new, original, and ornamental Design for a Trinket or Similar Article, of which the following is a specification, reference being had to the accompanying drawing, forming a part thereof.

In said drawing, the figure is a front view of a trinket showing our new design.

We claim:

The ornamental design for trinket or similar article, substantially as shown.

Signed at Boston, in the county of Suffolk and Commonwealth of Massachusetts, this 23rd day of December, 1922.

ADOLPH STUETZEL.
HERMAN W. BOHN.
